Munnik

[11] Patent Number: Des. 299,475

[45] Date of Patent:  Jan. 17, 1989

[54] COMBINED GOLF CARD HOLDER AND
INSERT THEREFOR

D. 228,202 8/1973 Quenot D19/86
D. 279,341 6/1985 Simmons D6/466

[76] Inventor: John H. G. Munnik, Margate, Natal
4275, South Africa

Primary Examiner—Charles A. Rademaker
Attorney, Agent, or Firm—Larson & Taylor

[] Term: 14 Years

[57] CLAIM

[21] Appl. No.: 810,250

The ornamental design for a golf card holder and insert thereof, as shown and described.

[22] Filed: Dec. 18, 1985

DESCRIPTION

[52] U.S. Cl. D19/78
[58] Field of Search D19/75-92,
D19/20, 22, 23; D6/466, 465

FIG. 1 is a front elevational view of a combined golf card holder and insert thereof showing my new design;
FIG. 2 is a side elevational view thereof;
FIG. 3 is a top plan view thereof;
FIG. 4 is another top plan view thereof with the insert member removed;
FIG. 5 is a front elevational view thereof;
FIG. 6 is a rear elevational view thereof;
FIG. 7 is a front elevational view of the insert member the side opposite being substantially a mirror image.
